UNITED STATES PATENT OFFICE

2,657,784

AUTOMATIC FEEDER

Lyman Paul Stoker, San Francisco, Calif.

Application June 2, 1949, Serial No. 96,708

8 Claims. (Cl. 198—21)

1

This invention relates to a feeding mechanism, and particularly an automatic feeding mechanism for continuously feeding short boards in batches of uniform length and the like, such as a box shook, on edge to re-sawing or other re-working machines.

Automatic feeders of this general character have been tried in sawmills and box factories, and their lack of success has been due to at least one of the several operating deficiencies or limitations mentioned below. Present equipment for feeding shook and the like, delivers boards with a minimum spacing of two or three inches between each piece, transmitting a destructive shock to the resaw or other re-working machines, in addition to materially cutting down the output. Boards or other units two inches or less in thickness and eight inches or more in length will not remain upright in feeding position on the feed table at desirable rates of speed for feed, with machinery presently available, when successive pieces are stripped off the end of the stack and delivered to the next machine. Likewise in some equipment now available, there is no coordination of action between the transfer rolls and the device for feeding stock to these rolls. Thus, jamming of the stock at the entrance to the rolls is a constant cause of failure of these machines. In feeding machines of this type, it is necessary that they be adapted to accommodate runs for different sized stock over a very wide range. While the machines of the present manufacture do provide for such adjustment, the adjustments often require special tools and in any event, are not easily made, with the result that the use of the machine is reduced by the time consumed in making the adjustments. In addition, machines now being used for this purpose are heavy, bulky pieces of equipment, which factors limit their usefulness materially, and prohibit their use where space limitations are critical.

Having in mind the foregoing and other deficiencies of previous methods and devices used in the work of the class concerned, it is a principal object of the present invention to provide an automatic feeder of improved design which will not only bring about greatly improved operation and enlarged capacities, but which will at the same time be compact and light-weight so that its usefulness may be extended to operations and locations not possible heretofore.

It is also an object to provide an improved device of the character described herein which will feed short pieces of lumber in substantially uni-

2

form pre-cut lengths, on edge to re-working machines at a high rate of speed and with a smooth continuous rate, all without intermittent motion or gap between pieces.

It is a further object of the present invention to accomplish the stripping of units or pieces of stock one at a time from a moving horizontal conveyor without disturbing the remaining stock on the conveyor to the extent that any piece therein loses its upright position. The same result can likewise be accomplished in feeding more than one individual piece at a time.

It is a further object of the present invention to provide a machine having readily accessible means built in as a part of the structure for quickly and conveniently making the adjustments required to accommodate changes in length, width and thickness of stock as may be required for each run, for making the changes in the rate of feed to the re-working machine and the changes in the number of units fed at any one time by the machine for re-working purposes, all without requiring the use of tools to accomplish these results.

It is also an object of the present invention to provide improved means of imparting opposite rotation to each of a pair of rolls acting synchronously from a single source of power with their axes parallel at all times, the rolls being resiliently mounted and the distance between them being readily adjustable.

It is a further object to provide a device of the class described which will accommodate the feeding of stripping of two or more units for simultaneous delivery to re-working machines.

Further objects are to provide a construction of maximum simplicity, economy and ease of assembly and disassembly and such further objects, advantages and capabilities as will appear to those skilled in this art and as are inherently possessed by the device and the invention described herein.

The invention further resides in the combination, construction and arrangement of parts illustrated in the accompanying drawing, and while there is shown therein a preferred embodiment thereof, it is to be understood that the same is merely illustrative of the invention and that the invention is capable of modification and change and comprehends other details of construction without departing from the spirit thereof or the scope of the appended claims.

Referring to the drawings:

Figure 1 is a top plan view of the device of the

present invention adapted for feeding box shook on edge to a resaw.

Figure 2 is a side elevational view of the device shown in Figure 1 viewed from the right hand side.

Figure 3 is a fragmentary detail in plan view with a portion broken away to expose the stripping mechanism.

Figure 4 is a fragmentary elevational view partly in section viewed from the right hand end of Figure 3.

Figure 5 is an exploded perspective view taken from the rear of Figure 3 to further expose the stripping mechanism.

Figure 6 is a diagrammatic plan view showing the stripping action and delivery of individual pieces to the feed rollers.

Figure 7 is similar to Figure 6 and together with it shows the progressive stations in the delivery of individual pieces to the feed rolls.

Figure 8 is a side elevational view partly in section from the left hand top portion of Figure 1.

Figure 9 is a transverse sectional detail taken on the lines IX-IX of Figure 8.

Figure 10 is a schematic view of the adjustable drive mechanism for the feed rolls.

Figure 11 is a fragmentary perspective view showing the manner in which the oppositely rotating feed rolls are adjusted with respect to the distance between their respective axes.

Figure 12 is a broken perspective view of the carriage to which the movable roll is attached.

Referring now more particularly to the drawings, in which like reference numerals have been used to specify and identify similar parts in the several views, the complete structure is best shown by reference to Figures 1 and 2. The device is mounted upon and carried by a framework of suitable height which consists primarily and essentially of a front post 15 and a rear post 16. These posts are spaced by means of carriage rails 17 and 18 which are preferably angle irons welded or otherwise secured thereto so as to present at either side an inwardly directed V of 90°, substantially as shown in Figure 9. Below rails 17 and 18, and likewise secured to the front and rear posts, are a pair of oppositely disposed motor rails or supports 20. Extending from and attached to the main frame just described are outrigger supports each of which consists primarily of a sidepost 21, a conveyor support 22, and crossbeams 23.

The conveyor or primary feed mechanism for the device, which is sometimes referred to in the art as a table-type feeder, eliminates much of the mechanism heretofore thought necessary. In this instance the table consists of a pair of conveyor chains 24 and 25, composed of individual flat links, which travel in the direction of the arrow 26. The chain drive sprockets 27 and 28 are mounted on drive shaft 30 and rotate as a unit. Idler sprockets 31 and 32 rotate on stub shaft 33 carried by identical supporting frame members 34 and 35. The conveyor chain 24 with its supporting frame 34 is mounted in a fixed position longitudinally with respect to the device. Although the conveyor chain 25 is substantially identical to 24, its supporting frame 35 is mounted on the conveyor support 22 in such a manner as to be movable and adjustable in position laterally with respect to conveyor chain 24 but maintained substantially parallel thereto. This adjustment is for the purpose of accommodating lengths of boards for any particular run. This lateral adjustment is made by rotating the

movable conveyor adjusting screw handle 36 which rotates the adjusting screw 37.

The motor 38 is the single source of power for operating this machine. There are, however, two takeoffs from the reduction gear 40 driven by this motor through a variable pitch pulley 41. The horizontal takeoff 42 drives through a pair of speed changing pulleys 43 to a pulley 44 through a jack shaft 45 to chain 46 which engages the sprocket which rotates shaft 30 and causes the conveyor chains 24 and 25 to move synchronously. The vertical takeoff 47 drives the rolls 50 and 51 in opposite directions synchronously and positively, in the manner shown diagrammatically in Figure 10. Referring to Figure 10, the vertical takeoff 47 is in a fixed position and because positive synchronous rotation is desirable, chain drive is preferably employed. The sprocket on takeoff 47 drives chain 52 which engages sprocket 53 driving roll 50, passes around idler sprocket 54 to sprocket 55 driving roll 51, and back to the sprocket of takeoff 47. Since the roll 51 is adjustable in connection with its spacing from roll 50, in the same plane as their respective axes, the drive shaft 56 is not a fixed point. In order to accommodate the length of drive chain 52 to the various adjustable positions of roll sprocket 55, idler sprocket 54 is mounted on the same carrier as roll 51 and its drive sprocket 55, so that when sprocket 55 is adjusted to a new position, an equal adjustment is applied to idler 54 at the same time. When the carriage is moved and with it sprockets 55 and 54 to a new adjusted position, such as that shown in broken lines in Figure 10 for example, the length of the path traversed by chain 52 remains substantially unchanged so that the initial tautness of the chain 52 is maintained without any other adjusting means or requirement.

Adjacent the rear post 16 and above carriage rails 17 and 18 is a bridge or plate 57 which supports the bearing 58 for the roll 50. The upper bearing 60 is supported by the upper bearing plate 61. As indicated before, the axis of roll 50 is maintained in a fixed position on the machine. The adjustable roll 51 is mounted on the carrier base plate 62 at one end thereof adjacent the roller 50. The carrier plate 62 has suitably mounted thereon along its longitudinal edges, angle irons 63 which outwardly present open V-shaped grooves as shown in Figures 9 and 12. These grooves, in conjunction with their corresponding grooves formed by carriage rail 17 and 18 serve as a raceway for ball bearings 64 permitting frictionless, resilient and accurate adjustment of the carriage in a horizontal plane. Since roll 51 is mounted on the carriage, the roll 51 can be moved to the precise adjustment to accommodate the thickness of the pieces for any run, as will be described later. It will also be observed that this construction prevents all other motion of the carriage except the lineal motion specifically provided and required. This is essential because the axis of roller 51 must be maintained parallel to the axis of roll 50 and in the same vertical plane. The lineal movement of the carriage bedplate 62 is accomplished by rotating the handle 65 which in turn rotates the screw 66 in fixed nut 67. Although the carriage roll 51, which is mounted thereon, is adjustable longitudinally as before described, it is also resiliently mounted to provide limited movement in any adjusted position. The nut 67 is not rigidly secured to the bracket 68 on the carriage plate 62 and which supports it. Rather, nut 67, which is carried by

crossplate 10, floats on studs 74 which pass therethrough and which are rigidly secured to the bracket 68. Compression springs 72 are adjustably secured between the free ends of studs 11 and the floating crossplate 10. The tension may be adjusted by the nuts 73 to bring about such tension as may be desired to cause suitable friction of the driving rolls 50 and 51 on the objects being fed, at the same time providing suitable resilience to accommodate the varying thicknesses and inequalities in the same objects.

Stripping mechanism

It will be observed from the arrow 26 shown in Figure 1 that the stack of objects or pieces 74 to be delivered either singly or in groups to the resaw or other operation pass linearly to the end of the device where the rolls are located. As the objects 74 approach the delivery end of the conveyors 24 and 25, they contact the aligning guide 75. As the progress of the individuals 74 continue, the first one 74, contacts trigger 80 which is depressed to the position shown in Figures 6 and 7. This causes the stripper mechanism, generally designated 81, to deliver the first unit 74, to the rolls. After delivery of the first unit, contact with the trigger delivery action is delayed for clearance of the preceding unit as will later be disclosed.

The delivery mechanism generally designated 81, comprises several elements including a double-acting air cylinder 82, and a four-way valve 83. The outlet ports 84 and 85 of the valve 83 are connected to opposite ends of the air cylinder 82 at 86 and 87 respectively through flexible connections 88 and 89. Compressed air is supplied to the valve through inlet air passage 90. Valve piston 91 passes longitudinally through the body of valve 83 and extends beyond either end thereof. It is actuated by the combined action of trigger 80, trigger spring 92, valve spring 93 which is a leaf spring, plunger pin 94 and bell crank 95. It should also be observed that the trigger 80 is likewise a bell crank being provided with arm 96. The air cylinder 82 and the valve 83 are mounted on and carried by bracket 97. The bracket 97 is mounted on fixed beam 98 and is adjustable along it to position it and accommodate it to various length objects 74. For quick action the bracket 97 moves freely within the fixed beam 98 and is retained in position by the screw 100 which is rotated by handle 101 to bear against the fixed beam 98.

Operation of the stripping device

The line 90 leading to the valve 83 is connected to a supply of compressed air which is delivered to the interior of valve 83. In the position shown in Figure 1, the object 74 has not yet contacted the trigger 80. The plunger 102 within the air cylinder 82 is retracted to the cocked position ready to act upon an individual object 74, when it is in a position to be fed to the rolls 50 and 51. Referring to Figure 7, when the object 74 contacts trigger 80, the tension of compression spring 92 is overcome by the physical depression of trigger 80. When the trigger 80 is depressed, the arm 96 is rotated clockwise out of contact with the valve piston 91. Pressure excited by leaf spring 93 on plunger 94 and bell crank 95 on the opposite end of valve piston 91 forces it to its extreme left position. In this position of valve 83, air is delivered through the outlet port 84 through line 88 to port 86 of the air cylinder 82 causing the plunger 102 to exert sudden pressure on the

end of the object 74, forcing it between the rolls 50 and 51. The extreme delivery movement of the plunger 102 is shown in dotted lines in Figure 7. The delivery and stripping of an individual object 74 to the rolls 50 and 51 is at right angles to the path of the conveyors. Accordingly, as soon as the individual 74 has passed the end of trigger 80, spring 92 rotates trigger 80 to return it again to the position shown in Figure 1 causing arm 96 to bear against valve piston 91 with a force greater than that exerted by spring 93 through plunger pin 94 and bell crank 95 on the opposite end of piston 91, and moves piston 91 to its extreme right position. In this position of valve 83 port 84 is open to atmosphere and compressed air is delivered through port 85 to the air cylinder through port 87 accomplishing the return of plunger 102 to its cocked position. For the sake of simplicity and ease of understanding of the operation, the above has described the structure and events which take place when the first object 74 or initial piece reaches the feeding position and contacts trigger 80.

It is apparent that as successive objects 74 approach the feeding position they will immediately contact trigger 80 and depress it. However, action of the plunger 102 must be delayed until the moment the individual item 74 immediately preceding it is clear of the following object 74. As shown in Figure 6, the object 74 delivered to the rolls 50 and 51 has passed a sufficient distance through the feed rolls to permit the conveyor chains 24 and 25 to advance the end of piece 74 so as to contact and depress the trigger 80. As shown in Figure 6, object 742 is not then in position to be fed to the rolls and therefore the action of the plunger 102 must be delayed until the object 741 has passed a sufficient distance through the rollers to clear the end of object 742 which immediately follows. This action and positioning is shown in Figure 7.

The mechanism accomplishing the delayed action of the stripper plunger 102 comprises the following: a square bar 104 mounted within the stripping beam 98 for rotatable movement; a timer lever 103 is mounted on the shaft 104 for rotating movement therewith, adjacent the rolls. At the opposite end of shaft 104 adjacent leaf spring 93 and above it is hub 105 having a depending tongue or lever 106 integral therewith. This hub 105 is carried in bracket bearings 107. In the position shown in Figure 4, the object 741 being fed into the rolls 50 and 51 engages the timer lever 103 preventing it from rotating in a clockwise direction under the action of spring 93. The hub 105 being mounted for clockwise rotatable movement with the timer lever 103 and rod 104, is maintained in the position shown in Figure 4 so that its depending tongue or lever 106 prevents leaf spring 93 from exerting any force against the plunger pin 94. It will be apparent that as the feeding of objects 741 continues through the rollers, the end will pass beyond engagement with timer lever 103 permitting leaf spring 93 to exert its pressure against plunger pin 94. When this is done, the valve 83 operates in the manner described before to cause the plunger 102 to exert pressure against the end of object 742 to feed it immediately into the rolls 50 and 51. This position is illustrated in Figure 7 and shows that object 742 follows immediately behind object 741 so that object 742 becomes, in effect, a continuation of object 741 without intervening space. This action continues as long

as objects 74 are placed on the conveyor chains 24 and 25.

The timing of the stroke of the stripper plunger 102 for objects 74₂ from the position of object 74₁ in the rolls, makes it possible to adjust the speed of the conveyor chains 24 and 25 to that only slightly greater than required to bring object 74₂ in contact with trigger 80 by the time object 74₁ has travelled far enough through the rolls that object 74₂ can be fed. Thus the stack of objects on the conveyor chains can proceed at a steady, uniform rate, without sudden accelerations as each piece is stripped from the forward end of the stack. It is this feature which permits long but thin objects or pieces to be fed on edge, and retain their upright feeding position throughout their travel on the conveyors, without external means of stabilizing.

I claim:

1. A feed mechanism for the continuous and contiguous feed of a series of subjects comprising in combination a trigger for engaging with each successive subject to be fed, a plunger for delivering a blow to the subject to feed the same to abut the immediately preceding subject in response to the engagement of said trigger, a pair of oppositely disposed rolls for accepting such feed, and automatic timer control means for positively delaying the action of said plunger until the subject immediately ahead has cleared.

2. A feed mechanism for continuous and contiguous delivery of boards to reworking machines comprising in combination a trigger for engaging each board as it reaches the point of delivery, a plunger for delivering a sudden blow to the board in the delivery position to abut the immediately preceding board in response to the engagement of said trigger, a pair of oppositely disposed rolls for accepting such delivery, and automatic timer control means for positively delaying the action of said plunger until the board immediately ahead of the board in delivery position has passed beyond it.

3. A feed mechanism for continuous and contiguous delivery of boards to reworking machines comprising in combination a trigger for engaging each board as it reaches the point of delivery, a plunger adjustable with respect to the length of board in any run, for delivering a sudden blow to the board in the delivery position to bring it into abutment with the immediately preceding board in response to the engagement of said trigger, a pair of positively driven rolls for accepting delivery of said boards, and automatic timer control means for positively delaying the action of said plunger until the board immediately ahead of the board in delivery position has passed beyond it.

4. In an automatic machine for continuously and contiguously feeding and stripping a batch of edge-supported rectangular objects having a substantially uniform pre-cut length, the combination which comprises a horizontal feeding mechanism adjustable normal to the direction of feed for supporting the said objects transversely thereon during the forward movement thereof, a pair of oppositely driven stripping rollers adapted to feed the said objects progressively, contiguously and in predetermined aligned relationship along a transverse delivery path, one of the said stripping rollers being adjustable and resiliently mounted to provide limited longitudinal movement in any adjusted position, and a delivery mechanism for the contiguous delivery of said objects to the said stripping roller oper-

able to delay the transfer of each successive object from the horizontal feeding mechanism to the said stripping rollers in such a manner as to prevent jamming at the entrance thereof.

5. In an automatic machine for continuously and contiguously feeding and stripping a plurality of edge-supported rectangular objects having a substantially uniform pre-cut length, the combination which comprises a horizontal feeding mechanism adjustable normal to the direction of feed for supporting the said objects transversely during the forward movement thereof, a pair of stripping rollers oppositely driven by a single chain drive and adapted to feed the said objects successively and in predetermined abutting relationship along a transverse delivery path, one of the said stripping rollers being laterally adjustable with respect to the other such roller without substantially changing the initial tautness of the said chain drive, and a delivery mechanism for the contiguous delivery of said objects to said stripping rollers responsive to the transverse movement of the said objects and operable to delay the transfer of each successive object from the horizontal feeding mechanism to the said stripping rollers in such a manner as to provide a continuous, contiguous feed of work through the rolls while substantially eliminating jamming at the entrance of the said stripping rollers.

6. In an automatic machine for continuously and contiguously stripping and feeding individual batches of edge-supported boards and the like having substantially uniform pre-cut length, the combination which comprises a power-driven horizontal feed mechanism adapted to support the work transversely thereon during the progressive forward movement thereof, means associated with the said horizontal feed mechanism for quickly adjusting the width thereof in accordance with the pre-cut length of the said work, a pair of power-driven rollers adapted to impart a stripping action to each of the said boards and to feed the same at a smooth and continuous rapid rate along a predetermined transverse delivery path while preserving the predetermined upright relationship thereof, and a delivery mechanism having means associated therewith automatically operable to delay the transfer of successive boards from the horizontal feeding mechanism to the said stripping rollers until the board immediately ahead is free and clear of the following board.

7. In an automatic machine for continuously and contiguously stripping and feeding individual batches of edge-supported boards and the like having substantially uniform pre-cut length, the combination which comprises a power-driven horizontal feed mechanism adapted to support the said work transversely thereon during the progressive forward movement thereof, adjusting means for varying the width of the said horizontal feed mechanism in accordance with the pre-cut length of the said work, a pair of power-driven rollers adapted to impart a stripping action to each of the said boards and to feed the same at high speed along a predetermined transverse delivery path without intermittent motion and without gaps between adjacent boards, one of the said stripping rollers being adjustably mounted to vary the spacing between the said rollers in accordance with the width of the said boards, and a delivery mechanism responsive to the transverse movement of the said boards and adapted to automatically delay the transfer of

successive boards from the horizontal feeding mechanism to the said stripping rollers in such a manner as to provide a continuous and contiguous feed of work through the said stripping rollers while preventing jamming at the entrance there- 5 of.

8. In an automatic machine for continuously and contiguously stripping and feeding a plurality of edge-supported boards and the like having substantially uniform pre-cut length, the combination which comprises a horizontal table-type feeder adapted to support the said boards transversely thereon during the progressively forward movement thereof, quick-acting means for manually varying the width of the said horizontal feeder in accordance with the pre-cut length of the said work, a pair of power-driven rollers adapted to impart a stripping action to each of the said boards and to feed the same at high speed along a predetermined transverse 15 delivery path in continuous motion and without 20

gaps between adjacent boards, one of the said stripping rollers being adjustably and resiliently mounted to provide limited longitudinal movement in any adjusted position, and a cam controlled pneumatic plunger operable to transfer successive boards from the horizontal feeding mechanism for contiguously feeding said boards to the said stripping rollers whenever the board immediately ahead is free and clear of the following board.
